UNITED STATES PATENT OFFICE.

HERBERT A. IRELAND, OF NORWICH, NEW YORK.

CARBURETER.

1,084,151.

Specification of Letters Patent.

Patented Jan. 13, 1914.

Application filed May 6, 1911. Serial No. 625,471.

To all whom it may concern:

Be it known that I, HERBERT A. IRELAND, of Norwich, in the county of Chenango, in the State of New York, have invented new and useful Improvements in Carbureters, of which the following, taken in connection with the accompanying drawings, is a full, clear, and exact description.

This invention relates to certain improvements in carbureters involving in addition to the feed for the gasolene or other liquid hydro-carbon and air, a float-controlled water-feed which together with the air and gasolene or other liquid hydro-carbon is adapted to be drawn into and thoroughly mixed in the carbureter and delivered as an explosive mixture to the engine.

Briefly described, the apparatus by which I carry out the objects of my invention comprises a casing having a mixing chamber therein, and a combined water and hydro-carbon feeder connected to the casing and divided into compartments having independent discharges into the mixing chamber, together with floats in the compartments carrying valves which coöperate with valve seats provided therefor on feed nozzles projecting into the compartments and carried by the cover of such compartments.

In the drawings—Figure 1 is a longitudinal vertical sectional view of a carbureter embodying the various features of my invention showing particularly the water chamber and float valve therein and the needle valve for regulating the amount of water admitted to the mixing chamber. Fig. 2 is a horizontal sectional view of the same carbureter taken on line 2—2 Fig. 1. Fig. 3 is a transverse vertical sectional view 40 through the same carbureter taken on line 3—3, Fig. 1.

As shown in the drawing, the apparatus consists of a cup-shape shell 1 divided by a central vertical partition 2 into opposite similar compartments 3 and 4 both of which are covered by a single cap 5 forming the top of the shell 1 and adapted to be secured thereto by suitable fastening means as bolts 6. The chambers 3 and 4 constitute reservoirs for receiving and retaining limited quantities of gasolene or other liquid hydro-carbon and water respectively and are provided with separate inlet or supply pipes 7 and 8 and separate outlet pipes or passages 9 and 10 both of which

latter discharge upwardly into a common mixing chamber 11 having an air inlet 12 and an outlet 13 adapted to be connected in any well known manner to the firing chamber or chambers of the engine not shown. The inlet conduits 7 and 8 are preferably secured to and extend downwardly from the central portion of the cap 5 and terminate at their lower ends in the upper portions of their respective chambers 3 and 4 and are formed with constricted outlets forming valve seats 14 and 15. Movable vertically within the chambers are similar floats 16 and 17 having upstanding valves 18 and 19 coacting with their respective valve seats 14 and 15 for separately controlling the passage of gasolene and water into their respective chambers 3 and 4. In like manner the outlets 9 and 10 which discharge into the mixing chamber 11 are provided respectively with valve seats 19 and 20 coacting with separate needle valves 21 and 22 which are engaged in threaded apertures in the upper side of the mixing chamber and are provided with external hand pieces 23 by which they may be adjusted at will to control the quantity of gasolene or water admitted to the mixing chamber.

It is now clear that when predetermined quantities of gasolene and water have been admitted to their respective chambers 3 and 4, the corresponding floats 16 and 17 will be operated to cause the valves 18 and 19 to close against their seats 14 and 15 and thereby cut off further supplies until they fall below predetermined levels, the floats 16 and 17 and the respective valves 18 and 19 serving to automatically regulate the supply of gasolene and water to their respective chambers 3 and 4. The valves 21 and 22 in the outlets 9 and 10 are adjusted at will and also serve to control the amount of gasolene and water from the chambers 3 and 4 to the mixing chamber 11.

The shell 1 is provided with suitable shoulders 25 adapted to be engaged by the floats 16 and 17 to limit their downward movement, thereby limiting the amount of opening of the valves 18 and 19.

The supply of the explosive mixture to

the engine may be regulated by means of a throttle valve —28— which is located as usual between the mixing chamber and outlet of the carbureter and may be operated at will by any suitable mechanism not necessary to herein illustrate or describe.

It is now clear that the gasoline or other liquid fuel together with the air are drawn simultaneously into the mixing chamber by 10 the exhaust produced by the piston of the engine, the fuel and water being introduced into said mixing chamber through separate jets and regulated by separate needle valves, and that the throttle is located between the 15 points of entrance of the fuel and water and the outlet of the carbureter leading to the engine, thus enabling the operator to control the mixture to a nicety according to the requirements of the engine under 20 varying loads. In other words the separate fuel and water jets discharge into a water chamber between the air inlet and throttle valve so that the inflowing jets of fuel and water are intercepted by the inflowing current of air in the mixing chamber where the 25 component parts of the mixture are thor-

oughly agitated and mixed before passing outwardly through the throttle valve to the engine.

What I claim is:

In carbureters, the combination with a casing having a mixing chamber therein, of a combined water and hydro-carbon feeder comprising a cup-shaped shell connected to one side of said casing, a vertical partition 35 dividing the shell into independent compartments, outlet conduits for said compartments leading into and discharging upwardly within the mixing chamber, a cover for said shell, feed nozzles projecting into 40 the shell through said cover and having valve seats at their discharge ends, floats in said compartments, and upstanding valves carried by said floats to engage the valve 45 seats of said inlet nozzles.

In witness whereof I have hereunto set my hand on this 1st day of May, 1911.

HERBERT A. IRELAND.
